SUPPORT BRACKET FOR HOSE NOZZLE

Nelson Severinghaus, Atlanta, Ga.
(213 Glenn Circle, Decatur, Ga. 30030)

Filed Feb. 22, 1973, Ser. No. 334,912

Term of patent 14 years

Int. Cl. D8—08

U.S. Cl. D6—112

FIG. 1

FIG. 2

FIG. 3

FIG. 4

FIG. 5

FIG. 6

FIG. 1 is a perspective view of a support bracket for a hose nozzle showing my new design;

FIG. 2 is a side elevational view thereof;

FIG. 3 is a side elevational view of the opposite side thereof;

FIG. 4 is a front elevational view thereof;

FIG. 5 is a top plan view thereof;

FIG. 6 is a rear elevational view thereof.

The broken lines shown in FIG. 1 are for illustrative purposes only and form no part of the claimed design.

I claim:

The ornamental design for a support bracket for hose nozzle, substantially as shown and described.
